UNITED STATES PATENT OFFICE.

WILLIAM F. BAKER, OF WAYNE, PENNSYLVANIA.

GAME BOARD.

Application filed September 9, 1921. Serial No. 499,410.

To all whom it may concern:

Be it known that I, WILLIAM F. BAKER, a citizen of the United States, residing at Wayne, in the county of Delaware, State of Pennsylvania, have invented a new and useful Game Board, of which the following is a specification.

My invention consists of a game board, which is composed of a card or sheet of suitable material forming a board, in which are perforations and on which are numerals adjacent to said perforations and somewhat loop-like members of fibrous or other pliable material having legs, which are adapted to be passed through said perforations and turned against the rear of said board, so as to retain the loop-like members in position, said legs, which are concealed from the front being of varying colors, the game being played by drawing out the loop-like members from the board, and the one who secures the largest number of members whose legs are of the same color and the largest score according to the numerals thereof, wins the game.

It consists also of a cover located on the rear of the card and attached thereto for concealing the colored legs of the loop-like members and assisting to retain the latter in position.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a front elevation of a game board embodying my invention. Figure 2 represents a rear elevation thereof. Figure 3 represents a vertical section of a portion on line 3—3 of Figure 1.

Figure 4 represents elevations of a number of loop-like members employed detached from the board.

Figure 5 represents a side elevation of one of said members, on an enlarged scale.

Figure 6 represents a perspective view of one of said members detached from the board, but in the condition when on the board.

Similar numerals of reference indicate corresponding parts in the figures.

Referring to the drawings:—

55 1 designates a sheet or plate which may

be formed of paste-board, card-board, or other suitable material and which I will designate hereafter as a board.

On the rear of this sheet 1 is a backing 2, which may be formed of the same material and is secured thereto by the string 3 passed through the backing and sheet or other suitable means.

On the face of the sheet are perforations 4 and on the sheet adjacent to the latter are 65 printed or otherwise marked numbers in rows, say 1 to 20, 21 to 30, 31 to 40, as many as may be desired.

5 designates loop-like members which are formed of pieces of cords of fibrous or other 70 material, bent for a portion of their lengths towards each other forming the legs 6, the ends of which are disconnected. These legs are passed through the perforations 4 and disposed against the rear of the board 1 and 75 held thereagainst by the pressure of the backing 2, while the faces of said members rest flat on the outer face of the board 1, and they only are exposed to be seen and grasped by players of the game, which is 80 not the case with the legs.

The latter are painted or dyed in various colors as at 7, some of them being unpainted or undyed as at 8, so as to retain the natural color of the card, which may be white, but 85 the portions of all of the cards on the outer face of the board are of the same color, which may be white, but this gives no intimation of the colors of the legs of the members which are concealed between the board 90 and backing, as has been stated.

In playing the game, a player draws out successively the loop-like members, as they may elect, the colors of the legs of which being unknown to them owing to the concealment of said legs, as has been stated. Then the one who has withdrawn the largest numbers of loop-like members whose legs are of the same color, or who scores the largest aggregate of the numerals on the board 100 at the perforations of withdrawn members, wins the game.

Having thus described my invention, what I claim as new and desire to secure by Letters Patent, is:—

1. In a game board, a board and loop-like members of fibrous material, which latter are adapted to be passed through the former, said members having legs of varying characteristics which are disposed upon 110

the rear of said board and bent for a portion of their length toward each other and held concealed there.

2. In a game board, a board having perforations therein, numerals on the board adjacent to said perforations, and loop-like members of fibrous material having legs of varying colors, which legs are passed through said perforations and disposed upon the rear of said board and bent for a portion of their length toward each other, and means for holding said legs in position and concealing them.

3. A game board consisting of a board having perforations therein, numerals on

said board adjacent said perforations and loop-like members of fibrous material having their ends disconnected forming legs which are adapted to be passed through said perforations and disposed upon the rear of said board and bent for a portion of their length toward each other, said legs being variously colored, and a backing plate on the rear of said board secured to the same and adapted to hold said legs in position and conceal the same.

WILLIAM F. BAKER.
